UNITED STATES PATENT OFFICE.

JULIA NIGRO, OF KANSAS CITY, MISSOURI.

EMBROIDERY-THREAD HOLDER.

Application filed April 19, 1926. Serial No. 103,013.

This invention relates to a holder for embroidery threads, in order that the thread may be conveniently supported upon the waist of an embroiderer or a suitable support as desired and has for its primary object to provide such a holder whereby single threads or skeins of various colors may be supported to permit the properly colored thread to be readily withdrawn from the holder without requiring the separation from a mass of various colored threads, the particular colored thread desired.

One of the main objects of the invention is to provide an embroidery thread holder of this character wherein skeins or single threads of various colors may be supported by the holder in spaced position so that the various colored threads will not become jumbled into a mass and also in order that the various colored threads may be reviewed at a glance, and the properly colored thread removed from the holder without interfering with the other threads thereon.

A still further object is to provide means whereby skeins or single threads of various colors may be readily attached to the holder and be maintained in position for ready removal therefrom.

Other objects will become apparent as the nature of the invention is better understood, the same comprising the novel form of embroidery holder hereinafter more fully described, shown in the accompanying drawing and claimed.

In the drawing wherein like reference characters indicate corresponding parts throughout both of the views:

Figure 1 is a front elevation of an embroidery thread holder constructed in accordance with the present invention, the same being shown as actually maintaining a plurality of various colored threads in association therewith, and

Figure 2 is a detail section through the holder per se.

Now having particular reference to the drawing, my novel embroidery thread holder constitutes the provision of a multi-ply strip of fabric 5 of suitable length and width that is provided at its opposite ends with lengths of ribbon 6—6 in order that said strip may be conveniently secured to the

waist of an embroiderer, or to, if desired, a support.

Said strip 5 consists of a front and rear 55 ply 7 and 8 respectively, and a center ply 9, the lower edge of which terminates within the lower edges of said front and rear plies 7 and 8. The three plies are secured together by a row of stitching 10 at the upper 60 edge thereof, and an additional row of stitching 11 in spaced relation to said upper edge.

Between the lower edges of the front and rear plies are secured spaced fabric tabs 12, 65 preferably by a row of stitching 13, said tabs consisting of overturned lengths of fabrics, the ends of which are arranged together and disposed between the lower edges of said front and rear plies 7 and 8 of the 70 waist strip 5, as clearly disclosed in Figure 2.

Secured to the inner portions of the tabs 12 at the free ends thereof are certain members of separable fasteners 14 that are adapted for interconnection with the other members 15 of said separable fasteners at the upper edge of the strip 5 in order that said tabs may be secured to the strip for retaining skeins or single variously colored threads A 80 in hanging spaced relation, the detachable connection between the strip 5 and the tabs permitting of the ready hanging of the single threads or skeins upon said strip.

As disclosed in Figure 1, the embroidery needle B may also be readily pinned into the strip 5 when not in use so as to prevent the misplacing of the same.

It will thus be seen that I have provided a highly novel, simple, and efficient form of embroidery thread holder that is well adapted for all the purposes heretofore designated. Even though I have herein shown and described the same as comprising certain detail structural elements, it is nevertheless to be understood that modifications may be had without affecting the spirit and scope of the appended claims.

Having thus described the invention, what I claim as new and desire to secure by Letters Patent is:—

1. An embroidery holder of the class described, a predetermined length strip of fabric, a plurality of thread supporting

fabric tabs secured in spaced relation at one end to a longitudinal edge of the strip, and detachable connections between the opposite ends of the tabs and the opposite longitudinal edge of the strip.

2. An embroidery holder of the class described, a predetermined length strip of fabric, a plurality of thread supporting fabric tabs secured in spaced relation at one

end to a longitudinal edge of the strip, detachable connections between the opposite ends of the tabs and the opposite longitudinal edge of the strip, and means at the opposite ends of the strip whereby the same may be secured to a support. 10

15 In testimony whereof I affix my signature.

JULIA NIGRO.
